(57) **CLAIM**

The ornamental design for a speaker enclosure, as shown and described.

DESCRIPTION

FIG. 1 is a front and right side perspective view of a speaker enclosure;

FIG. 2 is a front plan view thereof;

FIG. 3 is a right side plan view thereof, the left side being a mirror image;

FIG. 4 is a top plan view thereof;

FIG. 5 is a rear plan view thereof; and,

FIG. 6 is a rear and right side perspective view thereof. The broken lines in the figures represent portions of the speaker enclosure for illustrative purposes only and form no part of the claimed design.

1 Claim, 6 Drawing Sheets
